UNITED STATES PATENT OFFICE

MORITZ SCHENKEL, OF BERLIN-CHARLOTTENBURG, GERMANY, ASSIGNOR TO WESTINGHOUSE ELECTRIC & MANUFACTURING COMPANY, A CORPORATION OF PENNSYLVANIA

INSULATING MOUNTING FOR ANODE GRIDS

Application filed August 26, 1931, Serial No. 559,446, and in Germany August 29, 1930.

My invention relates to an insulating mounting for an anode grid and particularly for such grids as used in mercury arc rectifiers.

5 In the construction of mercury arc rectifiers, it has been customary to surround the anodes with a potential shield and to further protect the anode with a conducting grid. For purposes of convenience, this grid is 10 usually mounted inside of the shield and suspended from the shield by suitable supports, such as bolts or rivets.

To secure the best electrical performance, the grids are insulated from the shields in 15 which they are mounted. However, prior to my invention, considerable difficulty has been experienced in maintaining the insulation between the grids and the supporting shields.

This difficulty arose from the deposition of 20 conducting material on the grids and their supporting mountings. This conducting material eventually bridging any insulator used and electrically connecting the grids and their supporting shields. The deposited conducting material is mainly material blasted off or 25 "sputtered" from the anode head and carried from the anode by the rectifying arc.

I have discovered that this "sputtered" material moves in substantially a straight line or rather an oscillatory path in the arc stream. Since the "sputtered" material moves in substantially a straight line, it is possible to shield any object interposed in the arc stream by interposing a shield on each side of the 30 object to be protected. These shields will receive the "sputtered" material and protect the shielded object in substantially the same manner as an opaque shield intercepts light.

According to my invention, the insulating 35 mounting for the grid is so positioned with respect to the arc stream that some portion of the supporting shield is interposed between the "sputtered" material and the insulating surface. This is most conveniently accomplished by securing the insulators in housings

on the exterior of the shields and extending the grid supports in spaced relation with openings in the shield wall and having the supports received in suitable recesses in the insulator.

Other objects and advantages of my invention will be apparent from the following detailed description taken in conjunction with the accompanying drawing, in which

Figure 1 is a fragmentary sectional elevation of an anode shield embodying my invention,

Fig. 2 is a modification, and

Fig. 3 is a further modification.

The apparatus disclosed in the drawing 40 comprises an anode stem 1, an active head 2 and a suitable insulator 3 from which is suspended a substantially cylindrical shield 4, preferably of sheet material. Adjacent to the anode head 2 is an anode grid 5, preferably of conducting material, which is attached to the shield by a plurality of rod-like supports, such as the bolts 6.

The supporting bolts 6 extend through 45 openings 8 of greater diameter than the supports. The ends of the supports 6 are received by suitable insulators 10 mounted in a conducting housing 12 on the exterior of the shield. The junction between the supporting members and the insulating surface 50 being spaced from the opening in the shield wall. The spacing should be sufficient that any material travelling from the anode head through the opening 8 surrounding the support should not intercept the insulating surface 55 adjacent to the junction 13 with the supporting member. In this manner, the shield 4, or portions thereof, cause shadows on the insulating surface and prevent bridging from deposition of "sputtered" material.

The modification disclosed in Fig. 2 differs 60 from the disclosure of Fig. 1 only in that the supporting members 6 have been provided with down-turned extensions 15 so that the insulators may be used in direct compression

instead of having to support the weight of the grid in shear.

In the modification shown in Fig. 3, the housings 12 are substantially tubular projections extending outwardly from the surface 5 of the shield and substantially concentric with the passage 8 for the grid support 6. The tubular housing is supplied with an insulator 16 in the form of a bushing closing the open 10 end thereof. Preferably, the supporting members 6 are extended completely through the insulating bushing.

The use of a bushing in a partially open housing is particularly advantageous if it is 15 desired to make electrical contact to the supporting grid. Also, the supports extending completely through the insulating bushings facilitate the installation and positioning of the grids with respect to the shield.

While I have shown and described a specific embodiment of my invention, it is apparent that various changes and modifications can be made therein without departing from the spirit and scope of my invention. I 20 desire, therefore, that only such limitations shall be imposed as are embodied in the accompanying claims or as may be necessitated by the prior art.

I claim as my invention:

30 1. In a vapor electric device, an anode shield, a plurality of substantially tubular projections on the exterior of the shield, the shield having openings communicating with the interior of the projections, a grid in said 35 shield, supporting members for said grid extending through said openings into said projections and insulators in said projection for receiving the ends of the supporting members.

40 2. A mercury arc rectifier, an anode, an anode shield associated therewith, a grid in said shield, said shield having a plurality of openings therein, insulators mounted adjacent said openings and supports for said 45 grid extending through said openings and being carried by said insulators.

45 3. In a vapor electric device, an anode, a shield around the anode, a conducting grid in said shield, said shield having a plurality of openings therein, casings attached to the exterior of the shield and surrounding the 50 openings, supporting members for said grids extending through the openings into the casings and insulating members in the casings 55 for receiving the supporting members.

60 4. In a vapor electric device, an anode, a shield around the anode, a plurality of insulators mounted on the exterior of the shield, supporting members secured to said insulators and extending into the shield and a grid member supported by said members.

65 5. In a mercury-arc rectifier, an anode, an anode shield, a housing on the exterior of the shield, said shield having an opening communicating with the housing, a grid in the

shield, a supporting member for said grid extending through the opening into the housing and an insulator for the supporting member in the housing, said insulator being protected from the rectifying arc by said shield. 70

In testimony whereof, I have hereunto subscribed my name this 6th day of August 1931.

MORITZ SCHENKEL.
